TAG RING FOR HANGERS

Albert Haimowitz, New York, N. Y.

Application November 5, 1936, Serial No. 109,304

6 Claims. (Cl. 40—11)

This invention relates to new and useful improvements in a tag ring for hangers.

The invention has for an object the construction of a tag ring upon a hanger which is capable of releasably holding tags and other sheets of paper.

More specifically, it is proposed to characterize the tag ring by a vertical element which continues into a hook portion by which the hanger is supported and which simultaneously acts as a supporting medium for the tag ring.

Another one of the objects of this invention is to characterize the tag ring by the fact that it continues from a portion bent back along the hook portion mentioned in the previous paragraph and terminates at the top of the hook portion and continues into a ring comprising several helical turns. These turns may be manually forced apart when a card or other sheet element is placed between them.

Still further the invention proposes to adapt the tag ring for various types of hangers such as a pattern hanger, clothes hanger, and the like.

Still further the invention proposes the provision of a member mounted on one of the turns of the ring and manually turnable to separate the turns to facilitate the engagement of a card or other sheet element between the turns.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is an elevational view of a pattern hanger provided with a tag ring constructed according to this invention.

Fig. 2 is an edge elevational view of Fig. 1.

Fig. 3 is an elevational view of a modified form of hanger provided with a tag ring constructed according to this invention.

Fig. 4 is a fragmentary elevational view looking in the direction of the line 4—4 of Fig. 3.

Fig. 5 is a fragmentary transverse sectional view taken on the line 5—5 of Fig. 4.

Fig. 6 is an elevational view of another type of hanger embodying said invention.

Fig. 7 is an elevational view of still another type of hanger embodying the same invention.

With particular reference to Figs. 1 and 2 the tag ring, according to this invention, comprises a vertical element 10 which continues into a

hook portion 11 continuing into a support portion 12 bent back along the hook portion to the top thereof, and then continuing into a ring 14 comprising several helical turns 14^a, 14^b, etc. More specifically, there are two complete helical turns. It is between these turns that a card such as indicated by 15 may be supported.

The tag ring, in this form of the invention, is applied to a pattern hanger. This pattern hanger comprises a continuation 10^a from the vertical element 10 connecting with a bent portion 16 which in turn continues into an upward extending portion 17 terminating in a hook element 18 which is adapted to hook on to the element 10. The hook element 18 may be disengaged from the element 10 and then garment patterns such as indicated by dot and dash lines 19 or other articles may be hooked on to the hanger.

In Figs. 3—5 inclusive a modified form of the invention has been disclosed which is very similar to the prior form, distinguishing only in several respects. In this form of the invention the hanger also comprises a pattern hanger but has an arm 17' which is devoid of a hook, such as 18. Consequently, there is no arrangement for locking the patterns on the bent portion 16 of the hanger. In other respects this form of the invention is identical to the previous form and similar parts may be recognized by the identical reference numerals.

One of the turns of the ring 14, namely the turn 14^b, is formed with a reduced circular portion 20 upon which a member 21 is pivotally mounted. The shoulders at the sides of this reduced portion prevent the member 21 from sliding along the turn. This member 21 is provided with a cam portion 21^a upon one end thereof, and the handle portion 21^b upon the other end thereof. The handle portion may be manually moved to pivot the cam portion 21^a so as to separate the turns as indicated in Fig. 5. This facilitates the engagement of a paper card or sheet of paper between the turns. The other forms of this invention may embody the reduced portion 20 and the member 21.

In Fig. 6 another form of the invention has been disclosed which distinguishes from the prior forms merely in the construction of the hanger portion. According to this form of the invention the element 10 continues into a portion 10^a which then continues into the bend 16, which in turn continues into a side portion 17^a formed with a hook element 18^a at its free extremity and adapted to coact with the hook 11', 12' to lock

the hanger in its closed position. The hook portions 11' and 12' are slightly spaced from each other so as to form a loop portion into which the hook 18^a may engage.

5 In Fig. 7 another embodiment of the invention has been disclosed which distinguishes from the prior form merely in the construction of the hanger. This hanger is adapted to support clothes. It is formed by the element 10 continuing into a support portion 10^b, which in turn continues into a substantially horizontal shoulder portion 25, continuing into a transverse brace portion 26 extending beneath the shoulder portion 25 and which in turn continues into a cooperative shoulder portion 27 terminating in a hook 28 engaging the portion 10. In other respects this form of the invention is similar to the previous forms and similar parts may be recognized by the same reference numerals.

10 It is to be understood that the tag rings 14 and the card 15 may be of any desired size, also that the hangers may be used for hanging and classifying not only patterns of all kinds, but any other article.

15 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

20 1. A tag ring for hangers comprising a vertical element continuing into a hook portion of substantially inverted U-shape form continuing into a support portion bent back along the hook portion to the top thereof, and then continuing into a ring comprising several helical turns.

25 2. A tag ring for hangers comprising a vertical element continuing into a hook portion of substantially inverted U-shape form continuing into a support portion bent back along the hook portion to the top thereof, and then continuing into a ring comprising several helical turns, resiliently maintaining contacting positions and adapted

to be separated for the engagement of a card or sheet of material therebetween.

3. A tag ring for hangers comprising a vertical element continuing into a hook portion of substantially inverted U-shape form continuing into a support portion bent back along the hook portion to the top thereof, and then continuing into a ring comprising several helical turns, and a member on one of said turns rotative to separate them to facilitate the engagement of a card therebetween. 5

4. A tag ring for hangers comprising a vertical element continuing into a hook portion of substantially inverted U-shape form continuing into a support portion bent back along the hook portion to the top thereof, and then continuing into a ring comprising several helical turns, and a member on one of said turns rotative to separate them to facilitate the engagement of a card therebetween, 10 said member being pivotal upon a reduced portion of said turn. 15

5. A tag ring for hangers comprising a vertical element continuing into a hook portion of substantially inverted U-shape form continuing into a support portion bent back along the hook portion to the top thereof, and then continuing into a ring comprising several helical turns, and a member on one of said turns rotative to separate them to facilitate the engagement of a card therebetween, 20 said member being pivotal upon a reduced portion of said turn, the shoulders of 25 the reduced portion serving to hold the member from sliding. 30

6. A tag ring for hangers comprising a vertical element continuing into a hook portion of substantially inverted U-shape form continuing into a support portion bent back along the hook portion to the top thereof, and then continuing into a ring comprising several helical turns, and a member on one of said turns rotative to separate them to facilitate the engagement of a card therebetween, 35 said member being pivotal upon a reduced portion of said turn, and said member comprising a wedge portion at one end thereof and a handle portion at the other end thereof. 40
